UNITED STATES PATENT OFFICE.

HENRY MICHAEL LASHER, OF KANSAS CITY, KANSAS, ASSIGNOR TO THE KANSAS CITY GASOLINE COMPANY, A CORPORATION OF KANSAS.

METHOD OF TREATING HYDROCARBON OIL.

Application filed November 16, 1920. Serial No 424,471.

My invention relates to the art of refining hydrocarbon oils.

The object of the present invention is to coordinate the heating, cracking and other functions of my own and other processes so as to secure an increase in efficiency in speed of operation and percentage of conversion to selected fractions such as gasoline.

Stated very briefly I attain my object by 10 performing the heating function and the cracking function in separate chambers, through and between which a constant circulation is maintained, the oil itself conveying the heat energy necessary for its conversion, into the cracking zone. The method of circulating the oil is so arranged as to leave what I might term a "quiet oil zone" in the lower part of the cracking chamber, so that any carbon that is formed tends to 20 fall by gravity to the lowest part of the cracking chamber, where it can be readily drained off without adherence to the chamber walls, which in this case are not exposed to the external heat but instead are insulated to prevent the loss of heat supplied from within.

I shall disclose herein a suitable form of apparatus for practicing my new method, but it is to be understood that all changes there- 30 in lying within the scope of good engineering practice are contemplated by me. The illustration herein is diagrammatic only, as the details of construction can be readily supplied by those familiar with this art.

35 My process can best be understood by reference to apparatus such as illustrated in the accompanying drawings in which—

Fig. 1 is a diagrammatic plan view of a system for the practice of the invention; and

40 Fig. 2 is a similar diagram with parts in elevation, the fractionator and condenser being, however omitted.

I have included, for want of a better term, under the ordinary designation of catalyst the various materials used, namely, carbon in the form of coke or coal or a deposit of carbon on a matrix such as fire brick, calcium chloride or sodium chloride,

45 In my application Serial No. 365,351 filed March 12, 1920, I have described the use of carbon as a catalyst, and in my subsequent application, Serial No. 376,103, filed April 23, 1920, and Serial No. 393,424 filed July 1, 1920, I have described a modification in 55 which the catalyst is located on a shelf or

otherwise elevated above the bottom of the still. In all said applications the cracking still itself is heated directly and the heat communicated to the oil and to the catalyst through the oil. In the present case I employ the catalyst in the cracking still, but do not heat the latter directly. The catalyst is elevated above the bottom of the still however, so as to leave a clear space beneath to which I have referred as the "quiet oil zone".

Referring to the drawings: 1 is a still or container capable of withstanding considerable pressure and completely insulated externally with heat resisting material 1^a. 2 is a pipe connection leading from the inside of the still to the pump 3 which discharges into coil 4. 5 is a pipe connection leading from coil 4 to spray 6 which is located in the interior of the still in a position directly above the catalyst shelf 16 and catalyst 17 which in turn is located directly above the liquid level 15 as shown in Fig. 2.

Now, as to the operation, the oil is pumped into the still until it reaches a level indicated by No. 15 which is substantially higher than the top level of the coils in the furnace, thereby insuring the coils to be full of oil at all times. The pump is now started and the furnace is fired, the oil is circulated rapidly from the still through the coils out through the spray, over and through the catalyst, dropping back down to the liquid in the lower part of the still.

The operation is continuous and as the temperature of the oil rises to the point at which the catalyst acts upon it, cracking commences and some gases are made which are held within the still by keeping valve 12 closed until such gases generate the desired pressure under which the operation is to be conducted, then the valve is partially opened or closed to hold the desired pressure allowing the gasoline as it is made to flow into a receiving tank. A fractionator is interposed between the condenser and still, which is of the proper proportion to back-trap into the zone of action, any of the distillates which are not of desirable nature. It is noticed that the whole system is under like pressure, which serves the purpose of causing the oil to have a higher boiling point, and consequently increases the catalysis.

As the gasoline is made and drawn off, more heavy oil is pumped in through

valve 21 to maintain the proper oil level in the still.

I have shown run-back pipe lines 7 and 8 leading from the still 1 to the fractionator 9, from which pipe line 10 leads as usual to the condenser 11. The condensate is taken through the valve 12 to the receiving tank 13 fitted with a suitable draw-off valve V'.

The coil 4 in which the oil is circulated and heated, is enclosed within a furnace 14 of any suitable type. I have shown the coil as composed of straight sections which in practice have been found to work well with lengths up to twenty feet and diameters 15 from three to six inches. Alternate pipes are shown connected outside the furnace walls, and the straight members provided with heads which in practice are made detachable for purposes of cleaning. These 20 protruding portions of the coil may be insulated in any suitable manner, as for example by enclosure within a dead air space. The pipe lines 2 and 5 extending between the furnace and the cracking chamber may 25 also be insulated. I have found that the heat required may be accurately determined by using pyrometers at critical points such as 19 and 20, and the like, and while I am not limited to any particular primary source 30 of heat, it should in any event be regulable as regards its application to the coil 4.

The advantages of this system are at once seen, when we refer back to past experiences which have shown us that to crack oil with 35 heat, it is necessary to have a space relation, and as the tubes in this case are always full of rapidly circulating oil no cracking takes place and consequently no carbon is formed in them. Over-heating of the oil 40 and absence of cracking in the tubes is further assured by placing a pyrometer between the spray and the coil as shown at No. 19, by whose aid the proper temperature can be maintained by merely raising or lowering the fires in the furnace. The cracking 45 therefore takes place when the hot oil sprays down over the catalyst and any carbon that is formed, either adheres to the catalyst or drops down to the "quiet oil

zone" below. Pipe 2 leading from the still 50 to the pump is so arranged that the oil is taken from near the surface and does not disturb the oil in the lower part of the still, thereby leaving the carbon to settle in a quiet zone. The fact that the still is not 55 heated by fire, but rather merely maintains the heat of the oil by being thoroughly insulated, makes the still good for high pressures without danger.

It is readily seen that this process can also 60 be practiced without pressure by merely leaving valve No. 12 wide open. Also the process can be operated with the oil under pressure and the rest of the system without pressure by interposing an automatic relief 65 valve between the spray 6 and lead-in pipe 5, at the point marked V. Such valves are known in the art and need no description. The desired pressure used and the temperature of the still are varied according to the 70 character of the oil under treatment and of the product desired, the pressure being from atmospheric up and the temperature from 350° C. to 500° C.

What I claim is:

The method of cracking hydrocarbon oil which consists in heating and cracking the oil in separate chambers, while maintaining a uniform pressure and constant circulation through and between said chambers conveying the heat energy necessary for conversion and cracking in the oil itself from the heating zone to the cracking zone, and spraying said heated oil over a fixed catalyst in the cracking chamber in a position 85 above the bottom thereof so as to leave a quiet zone in the lower part of the chamber whereby any carbon formed therein will fall by gravity to the lowest part thereof, and uncracked heavy portions of the oil will 90 collect over said carbon, withdrawing the lighter cracked products from above the catalyst and returning the said heavier liquid products into circulation to and through the heating chamber from below said catalyst.

In testimony whereof I affix my signature.
HENRY MICHAEL LASHER.
